UNITED STATES PATENT OFFICE.

ARNOLD S. CUSTER, OF CINCINNATI, OHIO, ASSIGNOR TO HERRING-HALL-MARVIN
SAFE COMPANY, OF NEW YORK, N. Y., A CORPORATION OF NEW YORK.

SAFE OR VAULT.

1,035,164.

Specification of Letters Patent. Patented Aug. 13, 1912.

Application filed February 6, 1911. Serial No. 606,909.

To all whom it may concern:

Be it known that I, ARNOLD S. CUSTER, a citizen of the United States, residing at Cincinnati, in the county of Hamilton and State 5 of Ohio, have invented certain new and useful Improvements in Safes or Vaults, of which the following is a specification:

Burglarious attacks on safes or vaults have been heretofore attempted by the use 10 of high explosives, for instance, nitro-glycerin, and burglarious attacks have also been more recently attempted by the use of heat action produced by the electric arc, and laterally by the oxygen-acetylene flame, or gas 15 flame of similar nature, which produces a high degree of heat, locally applied, and most recently by the employment of the new agency named thermit, which produces an intense heat and exceedingly rapid penetration 20 of metal without noise and has proven to be a most dangerous method of attack upon safes or vaults.

It is the object of my invention to provide an improved construction for safes or vaults 25 which guards against all of the methods of attack mentioned, or methods of a similar nature.

My invention is applicable primarily to built-up burglar-proof constructions in safes 30 or vaults, and I have shown the same as applied to a vault structure.

The invention will be further readily understood from the following description and claims, and from the drawings, in which 35 latter:

Figure 1 represents a front elevation of a safe or vault door with the jamb adjacent thereto, partly broken away. Fig. 2 is a horizontal cross-section of the same on the 40 line $z-z$ of Fig. 1. Fig. 3 is a vertical cross-section of the same on the line $y-y$ of Fig. 1. Fig. 4 is a vertical section taken on a line corresponding to the line $x-x$ of Fig. 2. Fig. 5 is a cross-sectional detail of one 45 of the inside chrome-steel plates, and Fig. 6 is an enlarged sectional detail on the line $y-y$ of Fig. 1, showing the parts adjacent to the joint between the door and jamb.

The construction shown is a preferred 50 form, but it is obvious that my invention may be employed in other forms, a different number of inside layers of metal plates and insulation may be employed, and while I

have shown the invention in connection with a door of polygonal vertical cross-section, 55 known in the trade as a "square" door, it is obvious that the same may also be applied to so-called round doors, or doors of other shape, and the invention may be applied to suitable parts of the safe or vault structure. 60

1 represents the door and 2 the jamb. The door in the form shown comprises an outer plate 3 and an inner plate 4, of metal, preferably of tenacious, as contradistinguished from brittle properties, for instance open 65 hearth or Bessemer steel. The outer plate is preferably backed by a second plate 5 of metal, preferably of drill-resisting properties, for instance, so called chrome-steel, at the rear of which a further metal plate 6 is 70 located, the same being preferably of tenacious metal, as open hearth or Bessemer steel. At the forward face of the inner metal plate there is preferably a drill-resisting metal plate 7, preferably of chrome-75 steel. The arrangement of these plates is selective. The outer and inner plates are preferably of a size to encompass the width and height of the door in one piece. Alternate metal plate and insulation layers are 80 located between the plates described as located at the front and rear of the structure. As shown, one or more series of inside metal plates 8 are located between the forward and rear plates mentioned, each of the series 85 comprising a plurality of plates whose adjacent edges 9 are spaced apart for forming the space 10, preferably filled by an insulating filling 11. The respective series of inside plates, if more than one series, is employed, have their adjacent faces spaced apart, as shown by the space 12, the series of inside metal plates being spaced from the outer and inner plates by the spaces 13, 14. These last-named spaces are preferably 90 filled with an insulating material, as shown by the insulation layers 15, 16 and 17. The insulating material employed is preferably a non-conductor of electricity and heat. It 95 may be in the form of a hard-setting cement. 100 Any suitable insulating material, preferably insulating against the electric current and heat or burning, may be employed.

The series of inside metal plates are preferably of drill-resisting material, for instance, so-called chrome-steel. The chrome- 105

steel mentioned in practice usually comprises laminated sections of chromium or chrome-iron, indicated at 18 in Fig. 5, being a hard but brittle substance, held together by sections of steel 19 of tenacious properties. Other drill-resisting plates may be employed without departing from the spirit of my invention.

Surrounding the edge of the door, there is preferably an edge-framing 20, which may be a steel frame, located between the outer and inner metal plates of the door. This framing preferably surrounds the edges of the inside layers of drill-resisting metal and insulation, the series of metal plates being insulated from the framing by an insulating material 21. This insulating material 21 may be in the form of a sheet of insulation received at the inner face of the framing, between the framing and the alternate inside layers of metal and insulation of the door, thereby insulating said series of inside metal plates against the action of electricity and heat from the outer portions of the door. Each of the plates of the said series of plates is preferably surrounded by insulation, thereby insulating the same from each other and from the other parts of the structure.

The bodies of insulation between the adjacent edges of the individual metal plates of the inside series of metal plates are preferably very small in cross-section compared with the cross-sections of the individual inside metal plates. These individual inside metal plates preferably extend throughout a substantial part of the structure in which they are contained. The insulations between the adjacent edges of the individual metal plates of succeeding series of plates are preferably arranged in staggered or offset relation, as shown at *a*, *b*, and *c*, *d* in Fig. 4. I have shown each series comprised of four plates, having a horizontal and a vertical space between their adjacent edges, although it is obvious that the arrangement may differ without departing from the spirit of my invention.

My invention is particularly applicable to a built-up structure, this built-up structure being shown as comprising the forward and rear plates having the edge-framing located therebetween, between which plates and the framing the inside layers of the drill-resisting material or metal and insulation are located.

The framing may comprise an outer inwardly extending flange 22 and an inner inwardly extending flange 23. The plate 5 may be rigidly secured to the outer plate 3 by screws 24; and the outer plate rigidly secured to the outer flange by screws 25. The plate 6 may be rigidly secured to the plate 5 and the flange 22 respectively by screws 26 and 27. The plate 7 may be

rigidly secured to the inner plate 4 by screws 28, and to the inner flanges 23 by screws 29. The ends of the series of inside insulated plates are preferably received between the front and rear flanges of the edge-framing. The screws are preferably of drill-resisting metal and employed in suitable number and location to effect the purpose of forming a built-up structure in which the layers of inside plates and insulation are rigidly secured in place.

I have shown a preferred form of jamb employing my invention, in which 31 represents an outer plate which may have an angle-flange 32 extending inwardly therefrom.

33 represents a jamb edge-framing provided with an outer flange 34 secured to the outer plate 31 by screws 35. This outer plate may be of a tenacious steel, for instance Bessemer or open hearth steel. The jamb framing is preferably of steel. One or more inside metal plates, of which three are shown, at 36, 37, 38, are located adjacent to the jamb framing, and are preferably of drill-resisting material of the character mentioned. They preferably have layers of insulation shown at 39 between the same, and are separated from the outer and inner plates respectively by layers of insulation 40 and 41. They are spaced from the jamb framing at their edges by a layer of insulation 42, which may be in the form of an insulation sheet between the said edges of said layers of metal plates and insulations and the framing.

43 is an inner plate for the jamb, and 44 is a plate, preferably of drill-resisting material of the character mentioned between said inner plate and the jamb framing, the last-named plate being secured to the inner flange 45 of the jamb framing by means of screws 46 received therethrough and into said inner flange of said jamb framing, the inner plate being secured to the plate 44 by screws 47, preferably of drill-resisting metal. The outer side edges of said inside metal plates are preferably insulated from the metal framework, for instance the lining 48 thereof, by a layer of insulation 49.

The insulation prevents an electric circuit being formed with the inside insulated plates, so that even if the outer plates were penetrated by employment of the electric arc, the insulation layers would arrest further penetration thereby. The insulation layers also arrest further penetration by the oxygen-acetylene or similar flame, and by the action of the substance thermit, or similar substance, and by other known methods of attack by electricity, heat or burning, the tool-resisting plates preventing penetration by drilling or similar action. Even if the insulation were reached by one of the methods of penetration and it were forcibly lo-

cally removed, little further damage could be done, for the opening provided by such penetration would be in practice small in diameter, and, if accomplished for instance by thermit, which is of high specific gravity, and it were attempted to lead the thermit back into the door, the tendency would be for gravity to draw the thermit down along-side of the layer of insulation, where the 10 molten metal would pocket and immediately solidify. To continue the action, the molten metal must immediately run out of the way to permit the thermit to attack new metal. In practice only a small quantity of 15 thermit in comparison to the size of opening provided can be employed at an application, and while it acts quickly to melt the metal, it also loses its melting properties almost instantly and permits the metal to again solidify, and the attempt to dam up the thermit for holding it against the metal beyond the insulation has proven ineffectual.

50 may represent the ordinary vestibule of a vault and 51 is the body thereof, this body being of suitable material and shown broken away. The adjacent edges of the door and jamb are preferably provided with stepped jamb-surfaces, shown by the steps 52 on the jamb and the steps 53 on the door, 20 a portion of these steps being on the framings and a portion thereof formed by the overlapping of the plates.

In practice, the door preferably has a metal to metal fit with the jamb for preventing the 25 introduction of an explosive between the door and jamb. A usual method employed in burglarious attacks for introducing a high explosive such as nitro-glycerin between the door and the jamb, is to initiate 30 an opening or crack between the same by forcing a very thin wedge between the door and the door-jamb. In order to prevent the introduction of a wedge or tool to a sufficient extent to have a wedging action, and 35 to guard against the formation of an opening or crack between the door and jamb, or a springing of the metal thereof, in employing my invention, I have provided a shallow meeting joint and a lateral locking 40 joint between the door and jamb for preventing lateral separation between the same. Thus in the preferred form shown, I have 45 provided the door-jamb with an outer rabbet 54, which surrounds the jamb at the outer edge of its jamb-surface, and is preferably located in the outer plate 31, and the outer plate of the door is preferably provided with a peripheral shoulder 55, shown 50 formed by an edge rabbet 56 which surrounds the door. The shoulder is received in the rabbet of the jamb, the front face 57 of the door being shown as extending forwardly of the front face 58 of the jamb and having its outer peripheral portion rounded 55 as shown at 59. The outer rabbet 54 is shal-

low, and an attempt to introduce a wedge between its side wall and the side wall of the shoulder, would, if such attempt were successful, permit introduction of the wedge only to a very limited extent, namely to the 70 bottom of the rabbet 54, where the wedge would strike the bottom wall of the rabbet and further introduction thereof be prevented.

In order to prevent lateral separating displacement or springing between the door and the jamb, at the jamb-surfaces, I provide the same with mating laterally interlocking joints. These joints are shown as comprising a groove 60 in the jamb, a groove 61 in the door, a tongue 62 on the jamb received in the groove 61 of the door, and a tongue 63 on the door received in the groove 60 in the jamb, these tongues and grooves preferably surrounding the mating edges 85 between the door and jamb. The tongue and groove of the jamb are preferably formed in the jamb framing 33, and the tongue and groove of the door are preferably formed in the edge-framing 20 of the door, these tongues and grooves and the rabbets mentioned being preferably machined to an accurate metal to metal fit, with the tongues and grooves preferably located adjacent the outer edges of the door and jamb, 95 adjacent the rabbet and shoulder mentioned, when the door is seated in the jamb, for insuring against the lateral opening of the joint between the door and jamb, and against springing of the metal, by which a 100 crack between the same could be obtained.

64 is an air-obstructing member or packing between the walls of the groove and tongue and extending longitudinally thereof about the joint between the door and jamb 105 when the door is closed. It is shown received in a channel 65 in the wall of the groove, the tongue being provided with a projection 66, shown as a knife-edge rib, which extends longitudinally thereof, and is 110 adapted to enter the body of the air-obstructing packing when the door is closed for compressing said member, which is preferably a soft and slightly resilient body.

The rabbet and shoulder received thereby 115 and the tongue and groove preferably surround the jamb surfaces between the door and jamb. Any attempt to melt or burn through the door or jamb at the jamb surfaces would serve to securely unite the door 120 and jamb by the welding or fusing of the metal thereof. The inside metal plates 36, 37 and 38 may be arranged in series of individual plates whose adjacent edges are separated by insulation fillings 69 in staggered relation.

The door is suitably hinged to the body so as to seat the door in and withdraw it from its seat in the jamb with a movement at right angles to the front face of the door 125

for a slight distance, for insuring proper seating between the seating faces of the door and jamb, accomplished for instance by the cam-mechanism 67, the door being further permitted to swing on suitable hinges 68, these mounting means for the door however being well known and not particularly shown for that reason.

Suitable locking means, as a time or combination lock, or both, are provided for the door, not shown because well known.

Having thus fully described my invention, what I claim as new and desire to secure by Letters Patent is:

15. 1. A safe or vault door built up with outer and inner metal plates, an edge-framing with inwardly extending flanges having rigid connection with said metal plates, inside alternate drill-resisting metal plate 20 and insulation layers the former of which embrace drill-resisting metal plates of substantial area insulated from said edge-framing and received into the cross-sectional planes of said edge-framing extending at 25 right angles to the outer face of said door.
2. A safe or vault door built up with outer and inner metal plates, a stepped edge-framing to which said plates are rigidly secured, and alternate inside drill-resisting metal 30 plate and insulation layers whose planes of extension are parallel to the planes of extension of said first-named plates and comprising a plurality of series of separated drill-resisting metal plates arranged respectively in coincident upright planes and individually coincident in area with substantial parts of the areas of said first-named metal plates, said respective series of separated drill-resisting metal plates being received 35 into the cross-sectional planes of said edge-framing extending at right angles to the outer face of said door, the adjacent edges of said separated drill-resisting metal plates of said respective series being insulated from 40 each other, and said adjacent edges in adjacent series being in off-set relation.
3. A built-up safe or vault door comprising outer and inner plates of tenacious metal, inside plates of drill-resisting metal adjacent thereto, inside insulated layers of drill-resisting plates and insulating material between the latter, and an edge-framing for the door received about said insulated layers of drill-resisting plates.
5. 4. A built-up safe or vault structure comprising outer and inner plates of tenacious metal, inside plates of drill-resisting metal adjacent thereto, a plurality of series of inside drill-resisting metal plates separated 50 by layers of insulation from each other and from said first-named inside plates, each of said series comprising drill-resisting metal plates having spaces between their adjacent edges, the said spaces of alternate series arranged in staggered relation, the said spaces 55

having insulating material therein, and the individual plates of said plurality of series of inside drill-resisting plates being coincident in area with substantial portions of the area of said first-named plates.

5. A built-up safe or vault structure comprising outer and inner plates of tenacious metal, inside plates of drill-resisting metal adjacent thereto, a plurality of series of inside drill-resisting metal plates separated by 70 layers of insulation from each other and from said first-named plates, edge-framing received about said last-named series and insulated therefrom, each of said series comprising drill-resisting metal plates having 80 spaces between their adjacent edges, the said spaces of alternate series arranged in staggered relation, the said spaces having insulating material therein, and the individual plates of said plurality of series of inside 85 drill-resisting plates being coincident in area with substantial portions of the area of said first-named plates.

6. In a structure of the character described, the combination of outer and inner metal plates, a metal edge-framing rigidly secured between and adjacent to the outer edges of said plates, and alternate layers of metal and insulation between said first-named plates, said layers of metal being insulated from said first-named plates and said edge-framing.

7. In a structure of the character described, the combination of outer and inner metal plates, a metal edge-framing rigidly secured between and adjacent to the outer edges of said plates, alternate layers of metal and insulation between said first-named plates, said layers of metal being insulated from said first-named plates and said edge-framing, said metal layers composed of a plurality of plates having adjacent edges, and insulation between said edges.

8. In a structure of the character described, the combination of outer and inner metal plates, a metal framing rigidly secured between and adjacent to the outer edges of said plates, alternate layers of metal and insulation between said first-named plates, said layers of metal being insulated from said first-named plates and said metal framing, the said metal layers comprising a plurality of series of metal plates, the plates of each series having adjacent edges and insulation between said edges, the said adjacent edges of succeeding series being arranged in offset relation.

9. In combination, in a safe or vault, a door and a door-jamb, each comprising an outer metal plate, a stepped edge-framing, and alternate inside metal plate and insulation layer construction the layers whereof extend in parallel planes, and insulating material interposed between each of said metal 130

plate constructions and said respective stepped framings insulating the former from the latter.

10. In combination, in a safe or vault, a door-jamb comprising an edge-framing part and an outer and an inner metal plate secured to said edge-framing part, and inside metal plates and insulation arranged in alternate layers between said first-named metal plates, said inside metal plates insulated from said edge-framing part.

11. In combination, in a safe or vault, a body having a door-jamb thereon, an outer and an inner metal plate, a framing secured between the same, and inside metal plates and insulation arranged in alternate layers between said first-named metal plates, said inside metal plates insulated from said framing, and the said framing having steps 20 of said door-jamb thereon.

12. In a burglar-proof safe or vault, the combination of a jamb and a door, each of which is a built-up structure embracing an edge-framing and an outer plate, said edge-framings having stepped joints therebetween, and alternate inside layers of drill-resisting metal and insulation extending into those planes of cross-sectional projection of said stepped joints, which extend at right angles to the plane of projection of the outer face of said door when said door is closed, said layers of drill-resisting metal insulated from said edge-framings.

In testimony whereof, I have signed my name hereto in the presence of two subscribing witnesses.

ARNOLD S. CUSTER.
